ELECTRICAL CUT-OUT.

1,310,110.

Specification of Letters Patent.

Patented July 15, 1919.

Application filed July 15, 1916. Serial No. 109,439.

To all whom it may concern:

Be it known that I, LIONEL M. WOLFFSOHN, a citizen of the United States, and a resident of Hoboken, in the county of Hudson and State of New Jersey, have invented 5 an Improvement in Electrical Cut-Outs, of which the following is a specification.

This invention relates to electrical cutouts or switches and the like. One of the objects 10 thereof is to provide a practical device of the above nature of efficient and reliable action under conditions of hard use. Another object is to provide a device of the above type of simple and inexpensive construction. Other objects will be in part obvious and in part pointed out hereinafter.

The invention accordingly consists in the features of construction, combinations of elements and arrangement of parts which 20 will be exemplified in the structure herein-after described and the scope of the application of which will be indicated in the following claims.

In the accompanying drawings in which 25 is shown one of various possible embodiments of this invention,

Figure 1 is a front elevation, certain parts being removed in order to show the construction more clearly;

Fig. 2 is a similar view showing the parts 30 in another position;

Fig. 3 is a sectional view taken along the line 3—3 of Fig. 1; and

Fig. 4 is a side elevation.

Similar reference characters refer to similar parts throughout the several views of 35 the drawings.

Referring now to Fig. 1 of the drawings in detail, there is shown at 1 a casing, preferably of cast metal, and having formed 40 integral at each side the perforated supporting lugs 2. This casing has at its upper end an integral boss 3 and a similar guiding boss or shoulder 4 on the inner side of its lower 45 wall.

The parts 3 and 4 are drilled to provide bearings for a rod or spindle 5. The latter member is of enlarged diameter down to the upper shoulder 6, and the boss 3 is 50 drilled to afford a sliding fit with this enlarged part of the rod 5. This part of the rod is perforated, as at 7, adjacent its upper end, to receive a pin 7^a (Fig. 3) during the assembling operation, as will be hereinafter

more fully explained. Below the upper 55 shoulder 6 is a section of what may be termed an intermediate diameter, this intermediate portion of the rod being screw-threaded to receive a nut 17 hereinafter described. At the lower end of these threads 60 is another shoulder 7^b, and the rod below this shoulder is of a still smaller diameter, and is provided at its lower end with other threads 8, so as to permit of convenient attachment to any desired form of actuating 65 means, here diagrammatically indicated in Fig. 2 of the drawings by the part 9.

Each of the bearings of the rod 5 is provided with packing 10 held in place by a suitable cap 11 and screws 12. This packing, which is preferably of oiled felt, affords the slight lubrication required for the rod, and renders the joint waterproof.

Fitted upon the intermediate portion of the rod 5 is a heavy washer or ring 13, resting against the shoulder 6. This washer serves as a firm support for a spring 14 which resiliently holds in the desired shape a contact member 15, the end surfaces of which are formed in operative position to 80 coact with certain fixed contacts hereinafter described.

The lower surface of the contact member 15, which is preferably formed of copper, is supported by a washer 16, held in place by 85 a nut 17. Compressed between the nut 17 and the upper surface of the boss 4 is a spiral spring 18 normally holding the rod with its associated parts in its uppermost or circuit-opening position, as indicated in 90 Fig. 1 of the drawings.

About the reduced portion of the rod 5 and secured thereon inside the spring 18 and resting against nut 17, is a stop sleeve 18^a. This sleeve is of such length that its 95 lower surface will engage the boss 4 when the contact member is forced into its ultimate downward or circuit-closing position, and thus act as a stop to prevent a chance of breakage of the spring 14 or bending of 100 the parts if excessive actuating force be used. If desired, the sleeve 18^a may be secured in position on the rod 5 by providing an internal shoulder 18^b on the sleeve adapted to fit tightly against an upset portion 18^c on the rod, as indicated in Fig. 3 of 105 the drawings.

The above described parts slide evenly

within the casing 1 and there is cast integral with the rear walls of the casing, a pair of ribs or guides 19, against which the rear sides of the ends of the members 14 or 15 rest. These guides thus prevent rotation of the contact member and other moving parts, and accurately seat the bridging piece in its operative position.

Formed in the lower wall of the casing 10 is a seat or abutment 20 at one side, and a similar seat 21 at the opposite side, the latter seat extending to a higher point than seat 20. On the seat 20 is a piece of insulating member 22 bent upwardly as at 23 to rest against 15 a shoulder 24 formed in the side wall of the casing. This insulation securely supports in a position spaced on all sides from the casing, a fixed contact post 25, provided with a shank 25^a which passes outwardly through 20 an insulating bushing 26 in the wall of the casing, and is threaded upon its outer end. Co-acting with the threaded part of this member is an insulating washer 27 against which rests a metallic washer 28 and a nut 29 which serves to firmly anchor the contact 25 in position. Also positioned on the shank of contact 25 is another metallic washer 30 between which and nut 29 is gripped the bared end of the conductor 32 of an electric 30 circuit, by means of a nut 31. The apertures in the casing for the shanks 25^a, 34, are somewhat larger than the bushing 26 and shank 34 respectively, so that the posts 25, 33 will fit accurately upon their seats without requiring accurate drilling of the apertures.

Seated upon the abutment 21 is a contact 33, the shank 34 of which passes through the wall of the casing and is tightly clamped in position by a nut 35, this contact being in 40 electrical connection with the entire device. On shank 34 beyond the nut 35, the bared end of a conductor 36, which may if desired lead to ground, is gripped between a metallic washer 38 and the nut by an outer nut 39.

45 In assembling the device, the packing 10 and caps 11 are first secured on the casing 1 by means of the screws 12, after which the insulating member 22 is laid in position upon the seat 20. The contact posts 25, 33, are 50 then inserted in the casing and their shanks 25^a, 34, are passed outwardly through the apertures provided therefor, after which the insulated contact post 25 is secured in position by means of the insulating bushing 26, washer 27, and nut 29, and the grounded contact post 33 is similarly secured by means of the nut 35. The bridging piece 15, reinforcing spring 14, upper washer 13, lower washer 16, nut 17, spring 18 and sleeve 18^a, are 55 placed in the casing, and the rod 5 is then passed downwardly through the boss 3, then successively through the upper washer 13, reinforcing spring 14, bridging piece 15, lower washer 16, nut 17, and sleeve 18^a, 60 rounded by the spring 18, after which the

lower end of the rod is passed through the bushing 4. Then a pin 7^a is passed through the rod to facilitate relative rotation of the rod and the nut 17 to thread the nut upon the intermediate portion of the rod until the 70 bridging piece 15 and reinforcing spring 14 are secured tightly in position on the rod. The cover 40 may then be applied to the open face of the casing and secured thereon by means of the screws 41. It will thus be seen 75 that the entire device may be assembled through a single open face in the casing, that the parts are all operable with the cover on or off, and that all of the parts are readily available for inspection or removal, simply 80 by removing the single cover 40.

It may here be noted that by the term "cutout" is meant any device for interrupting or changing an electrical circuit, and that the term "casing" is also used in a broad 85 sense to denote any inclosing or embracing device.

In the use of this apparatus, the parts are normally in the position shown in Fig. 1 of the drawings, with an outer cover 40 held in 90 position by the screws 41 at each corner, closing the casing and maintaining it waterproof, and also proof against the entry of dirt or dust. With the parts in this position, the only live member in the entire device is 95 the contact 25, which is firmly and securely held in position. Accordingly, the remaining parts may all be electrically connected one with another, thus doing away with the necessity for careful construction or additional insulation, and improving the action 100 of the cutout when in contact-making position.

When it is desired to close the circuit, the rod 5 is moved downwardly by any suitable 105 device, and spring 18 compressed until the contact member 15 firmly engages the contacts 25 and 23. This contact member being resiliently supported, is permitted to spread slightly by the spring 14, thus rubbing the 110 contact surfaces clean and forming a connection of low electrical resistance and uniform pressure. Breakage of the spring is guarded against by the supporting washer 13 and by the arrangement whereby, how- 115 ever great an actuating force may be employed, the distortion of spring 14 is limited by the action of the sleeve 18^a, as above described.

Immediately upon release of the actuating 120 pressure, the parts are snapped back into the open position shown in Fig. 1 of the drawings. It is to be noted that although a large portion of the entire device is cast integral and is accordingly of extremely cheap construction, nevertheless the metal is so disposed that an accurate, even and reliable action is insured without the necessity for careful insulation, adjustment or cautious 125 use.

As various possible embodiments might be made of the above invention and as various changes might be made in the embodiment above set forth, it is to be understood that all

5 matter herein set forth or shown in the accompanying drawings is to be interpreted as illustrative and not in a limiting sense.

I claim as my invention:

1. In a device of the class described, in 10 combination, a casing, means adapted to hold said casing in position, a pair of contacts mounted in said casing, a rod extending through a wall of said casing and slidably mounted therein, a bridge contact carried by said rod in position to be brought 15 into bridging relation to said first contacts as said rod is slid within the wall of said casing and means integral with the inner surface of said casing to maintain said 20 bridge contact in alinement with said pair of contacts.

2. In a device of the class described, in 25 combination, a casing, means adapted to hold said casing in position, a pair of contacts mounted in said casing, a rod extending through a wall of said casing and slidably mounted therein, a bridge contact carried by said rod in position to be brought 30 into bridging relation to said first contacts as said rod is slid within the wall of said casing, means about said rod forming a waterproof joint at its slideable connection with the wall of said casing and means integral with the inner surface of said casing to 35 maintain said bridge contact in alinement with said pair of contacts.

3. In a device of the class described, in 40 combination, a casing, a rod extending through opposite walls of said casing and slidably mounted therein, a pair of spaced contacts mounted within said casing and respectively positioned on opposite sides of said rod, a bridging contact carried by said rod and movable therewith into bridging 45 engagement with said first contacts, means adapted to move said rod in one direction, and a spring tending to move said rod in the opposite direction, said casing being formed of cast metal and having integral therewith 50 a guide adapted to prevent swinging movement of said bridging contact.

4. In a device of the class described, in 55 combination, a casing, a rod extending through a wall of said casing and slidably guided therein, a pair of spaced contacts mounted within said casing and respectively positioned on opposite sides of said rod, a bridging contact carried by said rod and movable therewith into bridging engagement with said first contacts, means adapted 60 to move said rod in one direction, a spring tending to move said rod in the opposite direction, means holding said bridging contact in position and adapted to yield as contact-making pressure is applied, and means

associated with said rod and within said casing adapted to limit its contact-making movement.

5. In a device of the class described, in combination, a casing of cast metal having 70 formed integral on its inner surface a pair of guide ribs and a pair of supporting seats, a pair of contacts respectively positioned on said supporting seats, one of said contacts being insulated from said casing, means 75 adapted to connect the circuit terminals with said contacts, a rod extending through opposite walls of said casing in a direction transverse to a line connecting said pair of contacts and slidably mounted in said walls, 80 a yielding bridging contact carried by said rod and operatively related to said guide ribs to prevent rotation about the axis of said rod, means on said rod adapted to limit its sliding movement in a contact-making 85 direction, means on said rod against which said bridging contact is held, means adapted to slide said rod into contact-making position, and a spring urging said rod in the opposite direction. 90

6. In a device of the class described, in combination, a casing having on its inner surface a plurality of guide ribs and a plurality of supporting seats, contacts respectively positioned on said seats, one of said contacts being insulated from said casing, means adapted to connect the circuit terminals with said contacts, a rod extending through opposite walls of said casing and slidably mounted in said walls, and means 95 carried by said rod and operatively related to said guide ribs to prevent rotation of said rod about its axis. 100

7. In a device of the class described, in combination, a casing provided with an open 105 face, a detachable cover therefor, contact posts with reduced shanks, a rod passing through said casing, a bridging piece for the contacts, a locking nut for said bridging piece supporting the same and threaded to 110 receive said rod, the casing being apertured to receive said shanks and said rod, the rod being inserted in two substantially alined apertures and then threaded upon said nut, whereby the entire device may be assembled 115 through the open face of the casing.

8. In a device of the class described, in combination, a casing provided with an open face, a detachable cover therefor, contact posts with threaded shanks passing through 120 said casing, a bridging piece for the contacts, and a rod carrying said bridging piece, means for securing the bridging piece in position on the rod, the casing being apertured to receive said shank and said rod, 125 the bridging piece and contact posts being inserted into the casing through said open face, whereby all of said parts are operable with the cover on or off, and accessible upon the removal of the cover. 130

9. In a device of the class described, in combination, a casing provided with apertures and seats, contacts adapted to fit upon said seats and having shanks passing through certain of said apertures to the exterior of said casing and serving as binding posts, a rod passing through certain of said apertures and carrying a piece adapted to bridge said contacts, a cover adapted to fit upon a face of said casing, and means preventing the rotation of said rod, the machined surfaces of the casing, for the cover and the contacts, being all parallel or at right angles to the plane of said face.

10. In a device of the class described, in combination, a casing, contacts therein adapted to be connected to an electric circuit, a piece adapted to bridge said contacts, a nut for locking said piece in position, a rod passing through said casing and carrying said piece and threaded to receive said nut, shoulders in said rod adjacent either end of said threads, and other threads adjacent the reduced end of the rod to permit the rod to be threaded onto a suitable operating member, whereby in the assembling operation, the bridging piece may be placed inside the casing and the reduced end of the rod may be passed through said bridging piece and secured in position with respect thereto.

11. In a device of the class described, in combination, a casing, contacts therein adapted to be connected to an electric circuit, a piece adapted to bridge said contacts, a nut for locking said piece in position, a rod extending into said casing and carrying said piece and threaded to secure said nut, shoulders on said rod adjacent either end of said threads, and means associated with said rod during the assembling operation to permit relative rotation of rod and nut to thread the nut on the rod and thus secure the bridging piece upon the rod.

12. In a device of the class described, in

combination, a casing, contacts therein adapted to be connected to an electric circuit, a piece adapted to bridge said contacts, a nut for locking said piece in position, a rod passing through said casing and carrying said piece and threaded to receive said nut, shoulders on said rod adjacent either end of said threads, other threads adjacent the reduced end of the rod to permit the rod to be threaded onto a suitable operating member, whereby in the assembling operation the bridging piece may be placed inside the casing and the reduced end of the rod may be passed through said bridging piece and secured in position with respect thereto, and means secured to the casing for lubricating said rod at its bearings in the casing and excluding dust from the interior of the casing.

13. In a device of the class described, in combination, contact posts with threaded shanks, a rod threaded and provided with shoulders adjacent either end of the threads to receive and retain a piece adapted to bridge said contacts, a casing provided with apertures to receive said shanks and said rod, and nuts outside the casing securing the contact posts in position and serving as binding posts for circuit wires.

14. In a device of the class described, in combination, contact posts with threaded shanks, a rod, a bridging contact mounted thereon, a casing provided with apertures to receive said shanks and said rod, and nuts outside the casing securing the contact posts in position and serving as binding posts for circuit wires, the apertures for the shanks being large enough to allow the shanks to pass freely therethrough, whereby the contacts may be placed firmly in position irrespective of inaccuracies in the location of the apertures.

In testimony whereof I have signed my name to this specification this tenth day of July, 1916.

LIONEL M. WOLFFSOHN.
